(57) **CLAIM**

The ornamental design for a protection device for quadri-cycle, as shown and described.

DESCRIPTION

FIG. 1 is a perspective view of the protection device for quadri-cycle in accordance with the invention;

FIG. 2 is a front view of the protection device for quadri-cycle in accordance with the invention;

FIG. 3 is a side view of the protection device for quadri-cycle in accordance with the invention; and,

FIG. 4 is a top view of the protection device for quadri-cycle in accordance with the invention.

1 Claim, 2 Drawing Sheets

FIG. 1

FIG. 2

FIG. 3

FIG. 4
